(57) **CLAIM**

The ornamental design for a holder for rack-mounting audio equipment device, as shown and described.

DESCRIPTION

FIG. 1 is a perspective view of the holder for rack-mounting audio equipment.

FIG. 2 is a front elevation view of the holder for rack-mounting audio equipment.

FIG. 3 is a rear elevation view of the holder for rack-mounting audio equipment.

FIG. 4 is a top plan view of the holder for rack-mounting audio equipment.

FIG. 5 is a bottom plan view of the holder for rack-mounting audio equipment.

FIG. 6 is a left side elevation view of the holder for rack-mounting audio equipment; and,

FIG. 7 is a right side elevation view of the holder for rack-mounting audio equipment.

The broken line showing is for illustrative purposes and forms no part of the claimed design.
